ROLLER BEARER FOR PRINTING MACHINES

John W. Johnson, Manhasset, N. Y.

Application December 30, 1936, Serial No. 118,236

7 Claims. (Cl. 101—348)

The invention relates to roller bearers for printing machines, and more particularly to devices of this type adapted for use in bed and platen printing machines known generally as job presses.

In machines of the type to which the invention relates, the inking rollers have reciprocatory movement to ensure rolling contact with the type in a printing form and with an inking plate. To secure a proper inking of the type during the makeready of the press, it is necessary for the pressman to provide a backing for the form to secure a proper relation of the printing surface of the types to the plane of movement of the ink rollers, as well as a proper positioning thereof in relation to the platen in order to secure a clean sharp impression. If the face of the types be too high, the inking rollers may have a rubbing, instead of a rolling, contact therewith or with parts thereof, thus not only failing to properly apply the ink to the face of the types, but scraping ink from the roller and accumulating it upon the edge of said types.

To correct this condition, it has long been the practice to provide inking roller bearers locked in the chase with the type and the furniture by means of quoins. While this practice has secured a better inking of the type, it has been found objectionable because such bearers cannot be removed from a form without unlocking the form, and when a form is unlocked, type may become displaced and the position of the setup may be disturbed to an extent to necessitate a readjustment of the makeready of the press if it be desired to again run the press with the form therein.

With the type of roller bearers above referred to, the keeping of standing type in the forms cannot be resorted to unless the roller bearers are left in the form. This necessitates the provision of a large number of such bearers in a printing plant, and even when such bearers are used in the manner above referred to, accuracy in the adjustment of the plates is necessary when locking up a form.

With the above conditions in mind, I have provided roller bearers which may be applied to the chase after the form has been locked therein, and may be quickly removed therefrom and applied to another locked form without unlocking the form from which the plate is being removed.

In addition to the ready removability of the bearers and the possibility of quickly applying them to a chase, the construction of the bearers is such as to establish a definite relation of the roller track thereof to the surface of the type, so

as to ensure the proper contact relation between the inking rollers and the type. The composition of the inking rollers engages the bearers, thus ensuring not only a desired frictional engagement between these rollers and the bearers to 5 ensure the turning of the rollers during contact with the type, but the compressibility of this composition permits an automatic adjustment of the rollers to ensure the desired rolling contact with the type even though the bearer may be slightly 10 high in relation to the surface of the type.

Bearers embodying the invention may be inexpensively produced, and are secured to the chase in a manner to avoid their displacement in relation thereto after the form has been mounted 15 upon the type bed of the press.

The invention consists primarily in a roller bearer for printing machines embodying therein a vertically extending type high flange, a track adapted to be engaged by a composition inking 20 roller extending perpendicularly from the top of said flange, and a spring clip having upper and lower arms and a base secured to said flange, both of said arms extending parallel with said track and the upper arm converging toward the other 25 and being spaced below said track a distance permitting free flexure of said arm when applying the bearer to, or removing it from, a chase; and in such other novel features of construction as are hereinafter set forth and described, and more 30 particularly pointed out in the claims hereto appended.

Referring to the drawing,

Fig. 1 is a plan view of a locked form having roller bearers embodying the invention applied 35 to the chase, an inking roller being shown in operative relation to the form;

Fig. 2 is a front view of a roller bearer embodying the invention; and

Fig. 3 is a section on the line 3—3 of Fig. 1 40 upon a larger scale.

Like numerals refer to like parts throughout the several views.

In the embodiment of the invention shown in the drawing, the chase is shown at 10, the printing 45 form at 11, the furniture at 12 and the quoins at 13. A single inking roller is shown at 14, although a plurality of such rollers are usually employed in inking the form upon a printing press.

A roller bearer made in accordance with the 50 invention embodies therein a vertical type high flange 15. Carried by the top of this flange and projecting laterally thereof and perpendicularly thereto, is a roller track 16 consisting of a flat portion formed integrally with the flange 15. Be- 55

yond the opposite ends of the track 16 are downwardly directed guide ends 17 and 18 adapted to engage an inking roller and lift it into the proper bearing relation with the track 16.

5 The flange 15, track 16 and guide ends 17 and 18 are all formed of non-resilient sheet metal, these parts being integral one with the other.

Carried upon the inner face of the flange 15 and below the track 16 is a spring clip having a 10 base 19, a straight lower arm 20 and a top arm 21 converging towards the bottom arm 20. The free end of the arm 21 is upwardly flared as shown at 22. Both arms 20 and 21 are positioned below and extend parallel to the track 16.

15 The said clip is made of spring metal and the base 19 is of a width or height to space the upper arm 21 sufficiently below the track 16 to permit the free flexure of said arm when applying it to, or removing it from, one of the sides of the 20 chase 10. The bottom arm 20 of said clip is flat and positioned in the plane of the bottom edge of the flange 15.

The thickness of the material of the bottom arm 20 is only a few thousandths of an inch, so 25 that when it is applied to the chase, it will not raise the form materially in relation to the type bed of the machine.

30 The thinness of the metal stock permits the free flexure of the clip when applying it to, or removing it from, a chase, and the use of heavier stock is not required since the weight of the form will prevent displacement of the bearers during the operation of the press.

35 In using bearers embodying the invention, the form is made up in the usual manner and locked in the chase by means of the quoins 13, also in the usual manner. In making up the form, the usual practices are followed, and the bearers embodying the invention are applied to the chase 40 after the form has been made up and locked.

45 The mounting of the bearers in a locked form requires merely the application of the clip to a side bar of the chase, and the exertion of sufficient pressure to flex the upper arm 21 of the clip and permit the bearer to be forced over the side of the chase until the lower arm 20 passes beneath and in close contact with said side bar. The bearer may be shifted longitudinally thereof 50 along the side bar of the chase, although the downwardly directed guide ends 17 and 18 will aid in initially positioning the bearer sufficiently accurately.

55 In the accompanying drawing, the inclined guide ends 17 and 18 are shown as being positioned beyond the side bar of the chase. It is obvious that the downward angle of these ends may be such that the lowermost points thereof will be positioned from the bottom arm 20 of the clip or the bottom of the vertical flange 15 a 60 distance equalling the depth of the side of the chase, so as to permit the same bearers to be used with a number of chases of different sizes. If so used, the ends of the guides 17 and 18 will have such contact with the upper face of the 65 side bar of the chase as to contribute toward the avoidance of displacement of the bearer while a press is operating.

70 Duplicate bearers are used upon opposite sides of the chase, these bearers being reversible so that the same bearer may be used on either side of the chase.

If it be desired to remove the bearers from a chase, this may be done by merely pulling the bearer from the edge of the chase after the chase 75 has been removed from the type bed of the press,

this being accomplished without disturbing the quoins in any way, so that possible disarrangement of the types in the form is avoided.

During the printing operation, the inking rollers, in their movement from the inking plate to 5 the printing form, move longitudinally of the bearers, the composition of the rollers adjacent the opposite ends thereof engaging an end guide 17 or 18 upon each side of the chase in passing to the bearing track 16. The use of the guide 10 ends 17 and 18 avoids cutting of the composition of the roller by the ends of the guide track.

The material of the composition of the roller 14 is sufficiently compressible by the weight of the roller to not only ensure the turning of the 15 rollers by contact adjacent the opposite ends thereof with the bearers, but to permit the inked portion of the roller intermediate the bearers to assume a height which will ensure a desired rolling contact with the type or plates in the form. 20 By engaging the composition of the rollers with the tracks of the bearers, turning of the roller is assured, and with a rolling contact of the inking rollers with the type, there is a proper inking. The reciprocatory movement of the inking rollers 25 will ultimately bring them to the guide at the opposite end of the bearers, so that upon a reversal of the lineal travel of the rollers, the movement thereof caused by the bearers will be the reverse of that during the initial movement of 30 the inking rollers in relation to the bearers.

It is desirable that the guide ends 17 and 18 project beyond the ends of the vertical type high flange 15, since this avoids unnecessary labor in conforming the ends of said vertical flange 15 to 35 the angular inclination of said guides.

In the accompanying drawing, I have shown the clip as being secured to the flange 15 by means of rivets. It is obvious, however, that welding may be resorted to in securing said clip in the 40 proper position in relation to said flange.

From the foregoing it is obvious that the roller 45 bearers may be attached to, and removed from, a chase after the form is locked therein without disturbing the form or disturbing the type therein in any way, thus permitting the use of the same bearers upon different forms while permitting the forms, in connection with which they had previously been used, to be carried as standing forms ready for immediate future use. 50

It will be noted that roller bearers embodying the invention have no movable parts beyond the flexibility of the arms of the spring clip, and by reason of the use of this clip, the bearer may be used upon any size of chase so long as the length 55 of the track 16 is equal to the portion of the form to be inked.

The main advantages of bearers embodying the invention are that they may be applied to, and removed from, a chase after the form has been 60 made up without disturbing any of the furniture or the types, and that while inking, by reason of the contact of the printing roller composition with the track 16 and the height of the track, a proper 65 rolling contact of the inking rollers with the types is assured at all times. Other advantages have been set forth above.

It is not my intention to limit the invention to the precise details of construction shown in the 70 accompanying drawing, it being apparent that while a single spring clip of slightly shorter length than the vertical flange is shown, a continuous clip is not essential to the invention.

Having described the invention, what I claim 75

as new and desire to have protected by Letters Patent, is:—

1. A roller bearer for printing machines embodying therein a vertically extending type high flange, a track adapted to be engaged by a composition inking roller extending perpendicularly from the top of said flange, and a spring clip having upper and lower arms and a base secured to said flange, both of said arms extending parallel with said track and the upper arm converging toward the other, having an upwardly flared edge and being spaced below said track a distance permitting free flexure of said arm when applying the bearer to, or removing it from, a chase.

15 2. A roller bearer for printing machines embodying therein a vertically extending type high flange, a track adapted to be engaged by a composition inking roller extending perpendicularly from the top of said flange, and a spring clip having upper and lower arms and a base secured to said flange, both of said arms extending parallel with said track and the upper arm converging toward the other, having an upwardly flared edge and being spaced below said track a distance permitting free flexure of said arm when applying the bearer to, or removing it from, a chase.

30 3. A roller bearer for printing machines embodying therein a vertically extending type high flange, a track adapted to be engaged by a composition inking roller extending perpendicularly from the top of said flange, downwardly directed guides at the opposite ends of said track and said flange, and a spring clip having upper and lower arms and a base secured to said flange, both of said arms extending parallel with said track and the upper arm converging toward the other and being spaced below said track a distance permitting free flexure of said arm when applying the bearer to, or removing it from, a chase.

35 4. A roller bearer for printing machines embodying therein a vertically extending type high flange, a track adapted to be engaged by a composition inking roller extending perpendicularly from the top of said flange, downwardly directed guides at the opposite ends of said track and said flange, and a spring clip having upper and

lower arms and a base secured to said flange, both of said arms extending parallel with said track and the upper arm converging toward the other, having an upwardly flared edge and being spaced below said track a distance permitting free flexure of said arm when applying the bearer to, or removing it from, a chase. 5

5. A roller bearer for printing machines embodying therein a vertically extending type high flange, a track formed integrally with said flange extending perpendicularly from the top thereof and adapted to be engaged by a composition inking roller, and a spring clip having a straight lower arm, an upper arm spaced below said track a distance permitting free flexure of the arm 15 when applying the bearer to, or removing it from, a chase, and a base secured to said flange, both of said arms extending parallel with said track.

20 6. A roller bearer for printing machines embodying therein a vertically extending type high flange, a track formed integrally with said flange extending perpendicularly from the top thereof and adapted to be engaged by a composition inking roller, and a spring clip having a straight 25 lower arm, an upper arm spaced below said track a distance permitting free flexure of the arm when applying the bearer to, or removing it from, a chase, and having an upwardly flared edge, and a base secured to said flange, both of 30 said arms extending parallel with said track.

25 7. A roller bearer for printing machines embodying therein a vertically extending type high flange, a track formed integrally with said flange extending perpendicularly from the top thereof 35 and adapted to be engaged by a composition inking roller, downwardly directed guides at the opposite ends of said track and said flange, and a spring clip having a straight lower arm, an upper arm spaced below said track a distance 40 permitting free flexure of the arm when applying the bearer to, or removing it from, a chase, and having an upwardly flared edge, and a base secured to said flange, both of said arms extending parallel with said track. 45

JOHN W. JOHNSON.
